CASTING APPARATUS

Robert G. Wilson, Long Beach, Calif.

Application December 20, 1943, Serial No. 514,885

2 Claims. (Cl. 22—122)

This invention relates to apparatus for casting diamond core bits and has for its object the provision of an improved apparatus of this character. The invention aims to provide an improved apparatus of the type in which the diamonds are held in position in a mold by means of a vacuum and in which the metal to form the diamond core bit is poured over the diamonds.

The invention provides a casting apparatus comprising a carbon mold, preferably of graphite, having an annular channel for receiving the metal and the diamonds, vacuum means for securing the diamonds in position during casting, an interior member, preferably of graphite, in engagement with the mold forming at least a part of the inner wall of the mold and having an upwardly extending wall providing a chamber in which the metal is poured, together with means to distribute the metal into the mold, and means for securing and adjusting a blank bit in position above the annular channel whereby the metal of the bit becomes attached to the blank bit. In an advantageous embodiment of the invention, the graphite mold is mounted over a closed space capable of being placed under reduced pressure. The annular channel in which the metal is cast to form the diamond core bit is formed in part by a depending annular portion of the interior member. The side walls and bottom of the annular channel of the mold have a multiplicity of small holes connecting with the closed space in which the diamonds are secured in position by vacuum during casting. The means for holding and adjusting the blank bit is preferably a cylindrically shaped collar which fits into a cylindrical recess in the mold to support the collar (blank bit holder) in aligned spaced position above the annular channel of the mold. The blank bit holder comprises a blank bit and securing and adjusting means to align the blank bit in proper spaced relation with respect to the annular channel in the mold.

The interior member has upwardly extending side walls, preferably cylindrical, spaced inwardly from the blank bit to provide an annular space for a body of molten metal connecting with the metal in the annular channel which forms the bit. The chamber formed inside the upwardly extending side walls connects near the bottom with the annular space through a plurality of radially extending openings through which the metal poured into the chamber flows in all directions into the annular channel.

The bit holder and the bit are of cylindrical form having the same interior and exterior di-

ameters and the body of metal in the space surrounding the interior member connects with the metal on the interior side of the bit. In order to effect a suitable union or bonding of the bit to the bit holder, a plurality of spaced radial holes are formed in the bit holder near the lower extremity thereof and the metal flows into the holes uniting the bit holder to the bit.

These and other novel features of the invention will be better understood after considering the following discussion taken in conjunction with the accompanying drawings, in which:

Fig. 1 is a side elevational view, with parts in section, of apparatus embodying the invention;

Fig. 2 is a plan view along the line 2—2 of Fig. 1, and

Fig. 3 is a plan view along the line 3—3 of Fig. 1.

The apparatus illustrated in the drawings comprises a table or bench 1 of any suitable size and construction on which the apparatus for casting diamond core bits 2 is mounted. The cup-shaped base member 3 is formed of steel or iron and rests upon the table and has an opening in the bottom to which the air pipe 4 is connected as by threads. The air pipe is connected to a vacuum pump (not shown) and is provided with a quick action valve 5, vacuum relief valve 6 and a vacuum gage 7. In order to prevent small particles of metal being sucked through the air pipe, I preferably connect therein a filter 8 which is filled with any suitable small particles, such as small stones, marbles or the like. The base member has an inward recess 9 in which the exterior cylindrical edge portion and flat under surface of the graphite mold 10 rest, forming a close fitting joint. The depending cylindrical wall 12 has an annular channel 13 which defines the bottom and exterior cylindrical surface of the diamond core bit 14. The inner cylindrical face 15 of the depending wall 12 makes a close and sliding engagement with an annular exterior recess in the lower part of the interior member 16. The lower exterior cylindrical wall 17 of the interior member forms the interior surface of the core bit. The mold has an annular recess 18 for receiving the cylindrical blank bit holder 19 in proper alignment with respect to the annular channel 13. The blank bit 20 is threaded into the bit holder and there is sufficient play between the threads that the bit may be adjusted by means of the triangularly spaced adjustment screws 21. By means of these screws and the seating of the bit holder

in the recess 18, the blank bit may be positioned in precise alignment directly above the annular channel in which the bit is cast, whereby the exterior and interior cylindrical surfaces of both the blank bit and the bit are contiguous.

The interior member 16 has an upwardly extending wall with a cylindrical exterior spaced inwardly a sufficient distance from the interior surface of the bit holder to provide a space 22 for receiving molten metal. The interior chamber 23 connects with the space 22 at the bottom by means of a plurality of radially disposed holes 24. When molten metal is poured into the chamber 23, it flows radially in all directions through the holes 24 into the space 22 and then laterally into the annular channel below to form the bit.

While the mold and the interior member are advantageously formed of graphite or some other dense form of carbon they may be formed of refractory material. The form and arrangement of the interior member with respect to the mold and the blank bit makes it possible to obtain a relatively deep casting with a minimum of metal thereby increasing the density and uniformity of the metal in the bit and insuring a more uniform and positive engaging contact of the metal of the bit with the metal in the holes in the end of the bit holder.

The core bit and attached bit holder are severed from the cylindrical body of metal between the interior member and the blank bit holder by cutting out the interior on a lathe leaving the interior cylindrical surface of the blank bit holder co-extensive with the interior cylindrical surface of the core bit.

The depending wall 12 of the mold has a multiplicity of small holes 25 connecting the inside of the annular channel with the space 26 which may be placed under reduced pressure. One diamond 27 is held in position in each hole. As best shown in Fig. 3, the interior and exterior walls of the annular channel have ribs 28 and grooves 29 to form longitudinal grooves in the bit to facilitate the flow of water around the cutting face of the bit.

In forming a diamond core bit, the apparatus is assembled with the parts in the positions illustrated in the drawings and the valves 5 and 6 are manipulated to place the space 26 between the base cup and the mold under any desired vacuum, say, from about two to twelve inches of water. The diamonds are then set in the position shown, one diamond being spaced in each of the holes where it is held in position by the vacuum. The molten metal, usually an alloy steel,

is poured quickly into the chamber 23 from which it spreads out and flows radially through the holes 24 into the annular channel 13. The metal is poured into the interior member until it rises, say, about three inches, above the top of the bit filling the space 22. This creates a sufficient pressure to form the desired dense casting and the reserve of heat in the mass of metal give the proper extent of "draw" to the metal of the bit during cooling.

I claim:

1. An improved apparatus for casting diamond core bits which comprises a mold, an interior member constructed and arranged to cooperate with the mold to form an annular channel in which is poured the metal to form the bit, means for positioning and securing a multiplicity of diamonds in the annular channel during casting of the bit, a blank bit holder in concentrically spaced position around the interior member, means for securing the blank bit holder in secured alignment with respect to the mold, adjusting means for adjustably securing a blank bit in position with respect to the annular channel, a chamber for pouring metal into the interior member, an annular space between the interior member and the bit holder in communicating contact with the annular channel, and a plurality of openings in the interior member connecting the chamber with the annular space.
2. An improved apparatus for casting diamond core bits which comprises a mold, an interior member constructed and arranged to cooperate with the mold to form an annular channel in which is poured the metal to form the bit, means for positioning and securing a multiplicity of diamonds in the annular channel during casting of the bit, a blank bit holder in concentrically spaced position around the interior member, means for securing the blank bit holder in secured alignment with respect to the mold, a blank bit in adjustable engagement with the blank bit holder, said bit holder being held in precise position directly above the annular channel whereby the interior and exterior cylindrical surfaces of the bit and bit holder are contiguous, an annular space between the inside of the blank bit holder and the outside of the interior member, a chamber in the interior of the interior member, a plurality of holes connecting the chamber with the annular space, the annular space extending below the lower edge of the bit holder to enable the metal to flow radially from the annular space into the annular channel.

ROBERT G. WILSON.
